UNITED STATES PATENT OFFICE.

FEDERICO FIRPO AND JOSÉ ANTONIO BECERRA, OF CORDOBA, ARGENTINA.

OIL BURNER FOR LIMEKILNS AND THE LIKE.

Application filed April 10, 1928, Serial No. 268,977, and in Argentina December 24, 1927.

The present invention relates to oil burners; and it has for its main object to provide an improved burner of the type indicated which is designed primarily for heating lime-kilns and which is so constructed as to be efficient in its operation, and, at the same time, as not to affect the quality of the final product nor to damage the kiln structure through excess of heat.

10 In the accompanying drawing:

Figure 1 is a plan view of the improved burner;

Fig. 2 is a view of the front or nozzle end thereof;

15 Fig. 3 is a rear end view;

Fig. 4 is a longitudinal vertical section;

Fig. 5 is a vertical cross-section on line 5—5, Fig. 4; and

20 Fig. 6 is a fragmental vertical section of a lime kiln equipped with the improved burner.

Referring more particularly to Figs. 1-5, the burner, generally designated 6, is shown as consisting of a casing 7, the main portion 25 or body of which is divided by a horizontal partition 8 to form upper and lower chambers 9 and 10 to receive petroleum or other fuel oil and steam, respectively, as herein-after explained. Nozzles 11 and 12 are

30 mounted in the front ends of these chambers, one below the other; the oil nozzle 11 having a hexagonal central portion or body and a conical mouth, while the steam nozzle 12 is relatively flat and has an outward taper or 35 flare for spraying purposes. Both nozzles may be made adjustable, if desired.

The rear portion of the casing is constructed from an enlarged head 13, the outer or rear wall of which is provided with removable threaded plugs 14 and 15 to permit 40 access to the chambers 9 and 10 for cleaning or other purposes; the plug openings alining with said chambers, as will be understood. The partition 8 is provided at its rear end, 45 within head 13, with reversely-curved arms 16 and 17, so that at this point the partition has an S-shaped form, which is clearly shown in Fig. 5. The entire head is thus divided internally by the S-shaped partition 16, 8, 50 17 into two compartments 18 and 19, the former of which opens at its lower portion into the steam chamber 10, while the other compartment opens at its top into the oil chamber 9.

55 Inlets 20 and 21 are provided at the top

and bottom of the head for steam and oil, respectively, and can take the form of threaded nipples for connection to the steam and oil pipes (not shown); and a suitable filter 22 (Figs. 4 and 5) can be fitted in the oil inlet 60 21, if desired.

The arrangement above described provides for an ample superheating surface in order that the fuel may issue in liquid state and, owing to the pressure imparted to it in its 65 main reservoir, the fuel is projected from the nozzle 11 a distance of about 50 centimeters from the point thereof into the furnace 23 of the kiln 24 (see Fig. 6) where it meets steam issuing at a pressure of about 60 70 pounds from the nozzle 12 which distributes the oil over the material in the furnace, thus effecting the combustion of the lime and avoiding damage of the kiln structure.

The nozzles may be disposed in accordance 75 with the productive capacity of the kiln, that is to say, an ordinary burner may be provided with a fuel nozzle and a steam nozzle as shown in the drawing, but this same arrangement may also be duplicated or triplicated in accordance with the requirements of the plant, and the size of the oil and steam outlets may also be varied as desired in each case.

The improved oil burner is constructed by 85 casting it from brass in one piece, the walls being from 4 to 6 millimeters thick throughout. The nozzles 11 and 12 and the two plugs 14 and 15 provided at its head end for cleaning purposes, as well as the filter 22, 90 are also of brass. The nozzles are disposed in accordance with the furnace and capacity of the lime-kiln; the burner may be provided with one, two, or more steam and oil nozzles, the outlets thereof varying from 1 to 3 millimeters in width.

Having thus fully described and ascertained the nature of our said invention, what we claim and desire to protect by Letters Patent is:—

1. An oil burner, comprising an elongated body portion; a longitudinal partition in said body portion dividing the interior thereof into upper and lower longitudinal chambers; an enlarged head at the rear end of the body portion; a vertical S-shaped partition in said head and dividing its interior into two compartments, one opening at its top into one chamber, and the other opening at its bottom into the other chamber; liquid 105 110

fuel supply means opening into one compartment; steam supply means opening into the other compartment; and fuel and steam discharge nozzles attached to the front ends of the respective chambers.

2. An oil burner, according to claim 1, in which the burner body, its head and the

longitudinal and S-shaped partitions are formed conjointly by a single, one-piece metal casting.

In testimony whereof we affix our signatures.

FEDERICO FIRPO.
JOSÉ ANTONIO BECERRA.
